Specification of Letters Patent. Patented Feb. 6, 1917.

Application filed November 12, 1909, Serial No. 527,633. Renewed June 21, 1916. Serial No. 105,081.

To all whom it may concern:

Be it known that I, ERASTUS WOODWARD, of Somerville, in the county of Middlesex and State of Massachusetts, have invented 5 certain new and useful Improvements in Printing and Marking Machines, of which the following is a specification.

This invention relates to improvements in printing and marking machines and its 10 principal object is to simplify the construction of the same by providing independent mechanisms for operating the type-head and the inking pad.

Another essential feature of this device is 15 the provision of an automatic work-supporting table which will automatically adapt itself to any thickness of material.

Another feature is the provision of automatic mechanism for covering the inking 20 device to exclude dirt and dust and prevent evaporation and adapted to automatically uncover said inking mechanism only when it is necessary to ink the type.

Another feature of the inking device is 25 the utilization of an absorbent pad which carries the ink and which contacts with the inking roll in order to prevent an excess of ink from being fed to said roll.

In the accompanying drawings which 30 illustrate a construction embodying my invention, Figure 1 is a front elevation of the machine with the type head removed showing the parts in normal or non-operating position. Fig. 2 is an end elevation of Fig. 31 showing the type head, inking mechanism and automatic table in normal position. Fig. 3 is an opposite end elevation of Fig. 1 showing the clutch or driving mechanism with the driving pulley removed. Fig. 4 is 35 a vertical sectional view through the automatic work-supporting table. Fig. 5 is a sectional view on line 5—5 Fig. 1 showing the mechanism for automatically controlling the adjustment of the work-supporting 40 table. Fig. 6 is a sectional view on the line 6—6 Fig. 1 looking in the direction of the arrow and showing the operation of inking the type. Fig. 7 is a similar view to Fig. 6 showing the position of the parts with the 45 type-head about to make an impression. Fig. 8 is a front elevation of the inking device. Fig. 9 is a top plan view of same. Fig. 10 is a cross sectional view through

the center of Fig. 9. Figs. 11 and 12 are detail views to be hereinafter described. 55

Like letters of reference refer to like parts throughout the several views.

A is the bed of the machine and carries the post A' and main frame C. Mounted in the bearings C' in the upper part of frame 60 C is a rock shaft D carrying on its outer end the yoke arm D' secured thereto by the screw D². This arm D' carries mounted on its outer end the inking mechanism E. This rock shaft D is operated by the cam lever 65 D³ which carries the roll D⁴ operating in the cam track D⁵ on one face of cam F. The cam F is mounted on the driving shaft B which is mounted in bearings A² and B². The rock shaft G is mounted in 70 the bearings C² in the lower part of the frame C and carries the lever or type carrier G' secured thereto by the screw G². The type head J is secured by the clamp screw J² to the outer end of the lever G' and 75 the rock shaft G is operated by the cam lever G³ which carries the roll G⁴ which operates in the cam track G⁵ in the opposite face of the cam F. Mounted on the extension H of the bed A is a platen or work-supporting table H' (Figs. 4 and 5) and this table H' is mounted on the spiral screw H² which is vertically movable in said extension H. 80

H³ is a pin mounted in a hole in the extension H which prevents the table from rotating. 85

The lower end of the screw H² is pivoted at S³ to one end of lever S which carries a pin S⁷ to which is secured the lower 90 end of the spring H⁵, the opposite end of said spring being secured to the extension H. This spring H⁵ forms a cushion and support for the table when the impression 95 is being made. Mounted within the extension H and over the screw H² is a nut H⁶ which is rotatable within said extension.

H' is a collar loosely mounted over the screw H² and carries the arm H⁸ normally held against the stop H⁹ by spring H¹⁰. This 100 arm H⁸ carries the pin H¹¹ which is reciprocally movable in the hole H¹² in the extension H and has a beveled notch or recess H¹³ in which is mounted one end of a lock lever K which is pivoted at K' in the 105 extension H; the opposite end of said lever

is pivotally connected at K^2 within the yoke K^3 into which yoke K^3 is adjustably threaded the outer end of the rod K^4 . This rod K^4 is reciprocally mounted in the bed A of the machine and carries a sleeve K^5 secured thereto and which is mounted within the yoke lever K^6 pivoted at K^7 to the lower part of frame C , the upper end of said yoke lever K^6 carrying the roll K^8 which is operated by the cam k on cam face K^9 on the outer periphery of cam F . Mounted over the rod K^4 is a spring K^{10} which operates between the bed A and the adjustable nut or stop K^{11} to hold said rod K^4 outward and the lock lever K in the position shown in Fig. 5 whereby the projection K^{12} frictionally engages the nut H^6 to lock the same against rotation. The squared end of rod K^4 is for the purpose of adjusting the sleeve K^5 and thereby regulating the time during which the roll K^8 engages the cam k .

The cam k on the cam face K^9 operates during a certain point in the revolution of the cam F to actuate the lever K^6 and rod K^4 against the pressure of the spring K^{10} to move the lock lever K withdrawing the projection K^{12} from frictional contact with the nut H^6 to permit the same to rotate. The object of thus freeing the nut H^6 is to release the table H' through spiral screw H^2 to permit the table to be raised by the spring H^5 a predetermined amount to give sufficient tension to obtain a clear impression. The cam k immediately releases said lever K through means heretofore described allowing the projection K^{12} to bear on the nut H^6 which locks the table H' in adjusted position.

Pivoted at M in the outer corner of the extension H is a cam M' carrying a handle M^2 which in the position shown in Fig. 5 does not engage with the outer end of the lock lever allowing the operation of same as heretofore described, but when it is desired to allow the table H' to move up and down without locking the same in an adjusted position, the operator moves the handle M^2 until the cam M' engages and moves the outer end of lever K through the projection K^{12} out of frictional contact with nut H^6 .

S is a lever centrally pivoted at S' to the link S^2 pivoted on the lower side of extension H , the outer end of said lever being pivoted as heretofore stated, at S^3 to the lower end of the spiral screw H^2 . The opposite end of said lever S is pivoted at S^5 to the rod S^4 which may be connected with or operated by a treadle or other suitable device for depressing the table against the tension of spring H^5 to permit the insertion of the work, if it is not desired to have the table adjust itself automatically as described.

The type-head J is provided with a series of ring type disks J^3 rotatably mounted on a central shaft J^4 which is journaled in the

type head J . One end of the shaft J^4 projects outside the type head J and carries the knob J^5 for turning the shaft J^4 and for frictionally turning those of the type disks which are released by suitable pawls pivoted on the shaft J^6 so that the required figures or characters which are carried on the periphery of the disks may be moved into alignment for making an impression therewith.

The inking mechanism E comprises the casing E' which carries a hollow supporting stem E^2 mounted within the clamp E^3 in the lower end of the yoke arm D' . A screw E^4 is adapted to clamp the casing E' in position on said yoke arm D' (see Figs. 6 and 7). Journalized in the casing E' is a shaft E^5 which carries the inking roll E^6 . Mounted inside the casing and around this roll and in contact therewith is an absorbent composition E^7 , preferably felt, which retains or holds the ink and feeds the same to the pad roll E^8 .

One end of the shaft E^5 projects outside of the casing E' and carries screwed thereto the ratchet wheel E^8 . This ratchet wheel E^8 is adapted to be actuated by the pawl E^9 which is pivoted at E^{10} to the arm E^{11} secured to the rock shaft G by the screw E^{12} . The action of this pawl E^9 on ratchet E^8 is so timed that at each impression of the type head the arm E^{11} will operate through said pawl E^9 to intermittently move the ratchet E^8 and pad roll E^6 and thereby present a fresh inking surface on said roll to the type at each contact of said type therewith. This intermittent movement of the roll E^6 causes the ink to be evenly fed or distributed upon said roll by the felt E^7 which holds the ink inside of the casing E' . The intermittent movement of this roll within the felt also serves to remove from said felt any excess accumulation of ink or sediment on the roll.

To prevent evaporation of the ink when the type is not in contact with the inking roll E^6 , an automatic shutter E^{13} is provided which is reciprocally mounted in the ways E^{14} , said shutter carrying the stem E^{15} extending through the hollow stem E^2 . The projecting end of the stem E^{15} carries the notch E^{16} which engages with the spring latch E^{17} (see Figs. 11 and 12). This latch E^{17} is pivoted at E^{18} in a slot in the lower end of the hanger E^{19} , the upper end of which hanger is loosely mounted on the hub E^{20} in the upper end of the yoke arm D' . The spring E^{21} secured to the lower end of the hanger E^{19} acts against the extension E^{22} of the spring latch E^{17} to hold said latch in position within the notch E^{16} .

E^{23} and E^{24} are stops carried by hanger E^{19} on respectively opposite sides of the rib E^{25} on main frame C .

The operation of the shutter E^{13} is shown in Figs. 6 and 7, Fig. 6 showing the type

being inked by the inking roll E⁶ while the shutter E¹³ is withdrawn exposing the roll to the type. When the inking mechanism E is withdrawn from the type head by the movement of the yoke arm D', the stop E²³ engages the rib E²⁵ (Fig. 7) causing the shutter E¹³ to be closed upon the further receding movement of the inking mechanism. Mounted on the outer end of the driving

5 shaft B is a driving pulley N adapted to be continuously driven by any suitable power and normally free to rotate on said shaft, said pulley N being held in position by the bushing B² secured to the end of said shaft

10 15 B by the pin B³, (see Figs. 1 and 3).

N² is a sleeve securely pinned to the shaft B adjacent the inner face of the driving pulley N, said sleeve carrying an extension N¹⁰ upon which is mounted a vertically disposed

20 25 arm N¹¹ having pivoted thereto at N⁴ one end of a lever N³, the opposite end of said lever N³ carrying the friction roll N⁶ pivoted thereto at N⁵. This roll N⁶ carries a dog N¹³ on its upper face which is adapted to be normally retained adjacent to but out of frictional contact with the inside periphery of the hub N¹⁴ of pulley N. The lower face of the roll N⁶ is beveled at N¹⁵ and normally rests upon the wedge plate N⁸ which

30 35 40 45 50 55 60 65 70 75 80 85 90 95 100 105 110 115 120 125 130

is carried by a sliding sleeve N⁷ which is slidably mounted over the sleeve N², a recess N¹⁵ in said sleeve straddling over the extension N¹⁰ on the fixed sleeve N² thereby permitting a sliding movement of the sleeve N⁷ but causing the sleeve N² and shaft B to rotate when the sleeve N⁷ is caused to rotate. A spring P is pinned at one end to the extension N¹⁰ and at the other end to the sliding sleeve N⁷, said spring normally acting to pull the sliding sleeve N⁷ toward the pulley N. A cam strip N⁹ is secured to the sliding sleeve N⁷, the inner face of said cam strip normally engaging with a switch plate P² secured to the upper arm of the bell

45 50 55 60 65 70 75 80 85 90 95 100 105 110 115 120 125 130

crank lever P'. Lever P' is pivoted at P³ to the lower part of post A', the lower arm of said lever P' being pivotally connected with a rod C⁸ which may be operated by a treadle or any other suitable means for operating the switch plate P² to release the cam strip N⁹ and sliding sleeve N⁷.

P⁷ is a spring which is secured at one end to the bed A and at its other end to the lower arm of the bell crank lever P', said spring being adapted to hold the switch plate P² against the face of the cam strip N⁹.

The operation of this clutch is hereinafter more fully described. This clutch mechanism is not claimed in this application, but is shown, described and claimed in another application filed by me November 1st, 1909, Serial No. 525672.

The operation of the machine is as follows: The operator places the work or other article to be marked on the table H'; this

work may consist of either a single piece or a bunch of pieces of fabric, such as shoe linings, which are to be consecutively stamped. When the operator is ready for the impression to be made, the treadle connected with the rod C⁸ is pressed moving the bell crank lever P' against the pressure of the spring P⁷ which movement operates to throw the switch plate P² out of contact with the cam strip N⁹. The spring P automatically throws the sliding sleeve N⁷ toward the pulley N causing wedge plate N⁸ to lift the friction roll N⁶ until the dog N¹³ frictionally engages the inner periphery of the hub N¹⁴ causing the sleeve N⁷ and driving shaft B to rotate. The cam F now rotates with shaft B, the cam track D⁵ operating the roll D⁴, said movement acting through lever D³, rock shaft D and yoke arm D' to move the inking mechanism E outwardly from the position shown in Fig. 2 to that shown in Fig. 6. Simultaneously, the cam track G⁵ operates roll G⁴ which acts through cam lever G³, rock shaft G and lever G' to move the type head J backward from the position shown in Fig. 2 to that shown in Fig. 6. The relative movements of the type-head J and the inking mechanism E bring the type into contact with the inking roll E⁶, said roll having been automatically uncovered during this movement of the inking mechanism E by means of the shutter E¹³ being withdrawn through action of the hanger E¹⁹ which hanger has been carried forward by said movement of the inking mechanism E until the stop E²⁴ (Fig. 6) engages the rib E²⁵ checking any further movement of said hanger while the inking mechanism E continuing its movement to the position shown in said Fig. 6 causes the shutter E¹³ to be withdrawn through the action of the latch E¹⁷ mounted in notch E¹⁶ holding said shutter when the stop E²⁴ engages the rib E²⁵. The inking roll E⁶ being exposed, the type carried by disks J³ pressing thereon causes the type to be suitably inked. A continued movement of cam F causes the rock shafts D and G to oscillate in the opposite direction, said shaft D acting through lever G' to move the type head J forward and downward until the type engages with the work making an impression upon and marking the same (see Fig. 7) said type head being immediately lifted from contact with the work to its normal position as shown in Fig. 2. In the meantime, the rock shaft D operates the yoke arm D' to withdraw the inking mechanism E from the position shown in Fig. 6 to that shown in Fig. 2, the shutter E¹³ being automatically moved to cover the inking roll E⁶ during said movement through the action of hanger E¹⁹ when the stop E²³ engages the rib E²⁵ at the time the type is in engagement with the work. The inking mechanism now remains

in this position during the return of the type head J to its normal position as shown in Fig. 3.

When the parts have moved to the position shown in Fig. 2 after making the impression, the driving shaft B and cam F have made practically one revolution and the switch plate P² engages the projecting face of cam strip N⁹ forcing the sliding 10 sleeve N⁷ outward against the pressure of spring P withdrawing the wedge plate N⁸ from beneath the friction roll N⁶ causing the roll to drop and dog N¹³ to be thrown out of engagement with the periphery of the 15 hub N¹⁴. The driving shaft B is now at rest being disconnected from the pulley N which now operates idle upon the outer end of said shaft B. Assuming a bunch of pieces has been placed on the table H' by the operator to be marked: the type, upon engaging 20 with the topmost piece, forces the table H', spiral screw H² and nut H⁶ downward forcing the collar H⁷ against the spring H¹⁰ at the same time moving downward 25 the beveled pin H¹¹, the beveled surface H¹³ acting to force the outer end of the lock lever K outward, withdrawing the projection K¹² and allowing the nut H⁶ to rotate until the table H' has reached 30 a position to allow for the thickness of the bunch of pieces. During this operation the impression has been made by the type upon the upper piece on the table. Immediately before the upward or return movement of 35 the type head the spring H¹⁰ acts to force the collar H⁷ and beveled pin H¹¹ and nut H⁶ upward causing the beveled surface H¹³ to withdraw from the outer end of the lock lever K allowing the projection K¹² to frictionally engage the nut H⁶ preventing the 40 rotation of said nut and securely locking the table H' against upward movement. The operator now removes the top piece which has been marked and the treadle connected 45 with the rod C⁸ is again operated, which as heretofore described, throws the driving pulley into connection with the driving shaft B which operates to ink the type by means of the inking mechanism E, as described, 50 the type moving to the position shown in Fig. 7. The removal of the marked piece leaves the piece now to be marked below the lowest position of the type, so that before the type has reached its lowest point the cam k on the cam face K⁹ on the outer periphery 55 operates the roll K⁸ to move the rod K⁴ and lock lever K sufficiently to withdraw the end of said lever K from the contact with the beveled face H¹³. This leaves the 60 nut H⁶ free to rotate while the spring H⁶ forces the spiral screw H² and table H' upward a predetermined distance or a sufficient amount to carry the upper piece to be marked a sufficient distance above the low-

est position the type assumes to insure sufficient tension for securing a proper impression. This distance is gaged by the interval during which the cam k contacts with the roll K⁸ and holds projection K¹² out of contact with the nut H⁶, so that when the roll K⁸ is released or dropped by the cam k the projection K¹² engages the nut H⁶ locking the table H' in the predetermined position. 65 70

The distance the table H' moves upward can be adjusted, as heretofore described, by 75 means of the squared end of the rod K⁴ which can be operated to turn rod K⁴, and through the sleeve K⁵ and yoke lever K⁶ change the position of the roll K⁸, and consequently the interval during which said 80 roll contacts with the cam k. The adjustment of the squared end of the rod K⁴ moves the roll K⁸ either away from or closer to the face of the cam F, so that when the roll K⁸ strikes the bevel of the cam k and rises over 85 the apex of the cam and then returns to its normal position, the interval of contact would be less when the roll K⁸ is adjusted farther away from the face of the cam F and nearer the apex K. Therefore the 90 shorter the interval during which the roll K⁸ is held by the cam k, the less the distance in which the table H' moves upward, as the end of the lever K¹² is held a corresponding length of time out of frictional 95 engagement with the nut H⁶. In the meantime, immediately after the table H' has risen to the position described the type head J descends still farther, the type engaging 100 the upper piece of stock making the impression thereon and forcing the table H' down against the tension of the spring H¹⁰ and through the beveled surface H¹³ against the tension of the spring K¹⁰. Immediately upon the withdrawal of the type head the 105 nut H⁶ is frictionally engaged in the manner heretofore described locking the table H' in the position in which the type has moved the same. The piece upon which the impression has been made is now removed 110 by the operator and the remaining pieces are consecutively printed in the manner heretofore described. 115

If the operator desires to print the articles by placing the same consecutively on the table until a bunch is accumulated on the table instead of initially placing the bunch upon the table and removing the same consecutively the operation of the parts is identical with that heretofore described with the exception that instead the table H' rises the predetermined distance, but is forced downward by the type the amount which the table has moved upward plus the thickness of the stock which has been placed under the 120 type. 125

Having thus described the nature of my invention and set forth a construction em-

bodying the same, what I claim as new and desire to secure by Letters Patent of the United States is:

1. In a printing and marking machine, 5 the combination with a type-carrier, of an inking device for inking the type, independent mechanisms for separately carrying and operating said type-carrier and said inking device, continuously-operating driving mechanism normally disconnected from said independent mechanisms, means for connecting said driving mechanism with said independent mechanisms whereby said inking device and said type carrier coöperate to ink 10 the type and to separate to permit an impression from said type, and means for disconnecting said driving means from said independent mechanisms after said impression has been made.
  2. In a printing and marking machine, 20 the combination with a type-carrier, of an inking roll for inking the type, independent mechanisms for operating said type-carrier and said inking roll, continuously-operating driving mechanism normally disconnected from said independent mechanisms, means for connecting said driving mechanism with said independent mechanisms whereby said inking roll and said type carrier coöperate 25 to ink the type and to separate to permit an impression from said type, means for disconnecting said driving means from said independent mechanisms after said impression has been made, and means normally disconnected from and adapted to automatically 30 shift said inking roll at each impression to engage a different portion of the same with said type to ink the same.
  3. In a printing and marking machine, 40 the combination with a type carrier, of mechanism for operating said type carrier, an adjustable platen for supporting the work to receive the impression of the type and adapted to be operated thereby, and mechanism independent of the type carrier for automatically locking said platen in any position to which it has been moved by the impression of said type and for graduating the movement of said platen when released.
  4. In a printing and marking machine, 50 the combination with a type carrier, of mechanism for operating said type-carrier, an adjustable platen for supporting the work to receive the impression of the type and adapted to be operated thereby, mecha- 55 nism normally locking said platen in any position to which it has been moved by the type, and means independent of the type carrier for automatically releasing said locking mechanism when the type carrier 60 has reached a predetermined position to readjust said platen to receive the impression.
  5. In a printing and marking machine, a type carrier, mechanism for operating said type carrier, an adjustable platen for supporting the work to receive the impression of the type and adapted to be operated thereby, yielding means normally holding said platen to cushion the impression of said type, and means independent of the type carrier for locking said platen in adjusted position against movement toward said type carrier and for graduating the movement of said platen when released. 65
  6. In a printing and marking machine, 70 the combination with a type-carrier, of an inking device for inking the type, independent mechanisms for separately carrying and operating said type-carrier and said inking device, continuously operating driving mechanism normally disconnected from said independent mechanisms, means for connecting said driving mechanism with said independent mechanisms whereby said inking device and said type carrier coöperate to ink the 75 type and to separate to permit an impression from said type, and means for automatically disconnecting said driving means from said independent mechanisms after said impression has been made. 80
  7. In a printing and marking machine, 85 the combination with a type carrier, mechanism for operating said type carrier, an adjustable platen for supporting the work to receive the impression of the type and adapted to be operated thereby, independent mechanism for locking said platen in printing position and for releasing said platen to permit the upward movement of the same, and means independent of the type carrier 90 for automatically adjusting said mechanism to limit the upward movement of said platen. 95
- In testimony whereof, I have signed my name to this specification in the presence of two subscribing witnesses, this fifth day of November, A. D. 1909.
